UNITED STATES PATENT OFFICE.

ROBERT M. APPLETON, OF BOSTON, MASSACHUSETTS.

DESIGN FOR AN UNDERVEST.

SPECIFICATION forming part of Design No. 29,085, dated July 19, 1898.

Application filed April 17, 1897. Serial No. 632,676. Term of patent 7 years.

To all whom it may concern:

Be it known that I, ROBERT M. APPLETON, of Boston, in the county of Suffolk and State of Massachusetts, have invented a new and original Design for Ladies' Undervests, of which the following is a description, reference being had to the annexed drawing, forming a part of this specification.

The drawing represents a front view of a ladies' undervest.

The leading feature of my design consists in the shoulder and waist bands of close pattern separated from each other by a band of open or loose pattern extending across and to the sides of the garment and having a width substantially equal to the said shoulder and waist bands.

In the drawing, *b* and *c* designate the upper or shoulder band and the waist band, respec-

tively, and *a* designates the intervening band of open or loose fabric.

d designates the skirt portion of the garment, and *e* the sleeves.

2 and *3* designate the abrupt boundaries of the band *a* where said band meets the bands *b* and *c*.

What I claim is—

The design for an undervest substantially as herein shown and described.

In testimony whereof I have signed my name to this specification, in the presence of two subscribing witnesses, this 15th day of April, A. D. 1897.

ROBERT M. APPLETON.

Witnesses:

ARTHUR W. CROSSLEY,
GEO. N. GODDARD.
